UNITED STATES PATENT OFFICE.

BURNHAM C. STICKNEY, OF ELIZABETH, NEW JERSEY, ASSIGNEE
TO UNDERWOOD TYPEWRITER COMPANY, OF NEW YORK, N. Y.,
A CORPORATION OF NEW JERSEY.

STENCILING-MACHINE.

No. 853,606.

Specification of Letters Patent.

Patented May 14, 1907.

Application filed July 11, 1906. Serial No. 325,565.

To all whom it may concern:

Be it known that I, BURNHAM C. STICKNEY, a citizen of the United States, residing in Elizabeth, in the county of Union and State 5 of New Jersey, have invented certain new and useful Improvements in Stenciling-Machines, of which the following is a specification.

This invention relates to that class of duplicating machines, in which a wax stencil is secured upon a rotatable cylindrical ink screen, and successive sheets of paper are pressed against the stencil by a yielding roll during the revolution of the cylinder and thereby stenciled; and particularly to that variety of stenciling machines in which the stencil cylinder and the pressure roll cooperate to form a gage for the leading edges of the paper sheets, and in which a stop arm is adjustable around the cylinder to determine the initial rotative position thereof, whereby the stenciled matter can be caused to appear at any desired point upon the sheet.

It has been the practice to provide a stop which yields during the advance of the cylinder, but which is unyielding during the retraction of the cylinder, so that when the cylinder is rotated to stencil the sheet, it passes said stop at the completion of its revolution, and is then dropped back against the stop by the operator, thereby positioning the cylinder to receive the first sheet of paper.

The principal object of my invention is to avoid the objections which exist to this method of positioning the cylinder, and to this end I provide a stop which positively arrests the advance of the cylinder at the completion of its revolution, whereby the cylinder is positioned for the reception of the next paper sheet independently of any attention on the part of the operator, who has simply to turn the cylinder as far as it will go. I also provide means for yieldingly holding the cylinder against the stop, so as to prevent recoil of the cylinder when it strikes the stop. After the sheet is inserted the operator has simply to press a key, the effect of which is to release the cylinder from the control of the stop, so that it may make another revolution until again arrested by the stop. It is desired sometimes to give the cylinder several revolutions without printing, and by this time both the stop and the yielding de-

vice are silenced by the same device that casts off the pressure roll, thus leaving the cylinder movable in either direction without obstruction.

In the accompanying drawings, Figure 1 is a side elevation illustrating my improvements applied to a stenciling machine. Fig. 2 is a sectional plan showing details of the stop mechanism. Fig. 3 is a perspective of the parts seen at Fig. 1. Fig. 4 is another perspective of the mechanism showing particularly the pressure roll releasing device. In the foregoing figures the parts are shown in normal positions, the stencil cylinder being at its initial rotative position, and with the roll pressing against the cylinder. Fig. 5 shows the pressure roll released, and the cylinder stop mechanism silenced.

A large cylindrical ink screen 1 is suitably mounted for rotation, as for instance in the manner shown in the Kunath patent No. 824,695. The cylinder is rotated by means of a handle 2 projecting from an arm 3, adjustably secured by thumb screws 4 to the rim 5 of the screen 1. Upon its inner face said arm is formed with a lug 6. In the path of the lug is a stop 7 provided upon the end of a lever arm 8 pivoted at 9 upon the framework 10 of the machine. The paper sheets 11 are laid upon a feed-board 12 and guided by a throat 13, 14, into the bite of the cylinder 1, and a pressure roll 15, the latter pressing the paper against the stencil sheet that is secured upon the cylinder 1, so that when the latter is rotated by the handle 2 in the direction shown by the arrow the paper sheet 11 is drawn between the rolls and stenciled. At the completion of the revolution of the stencil cylinder, the lug 6 thereon is arrested by the stop 7, so that the cylinder can advance no farther. By this time the stenciled paper 11 has been delivered from the machine, and a fresh sheet is inserted into the bite of the rolls. In this manner the desired location or registry of the stenciled matter upon the sheet 11 is secured. If it be desired to stencil the matter either higher or lower upon the sheet 11, the stencil cylinder 1 must have a different initial position, and to this end the stop arm 3 is made adjustable around the rim 5 of the stencil cylinder, said arm being provided with claws 16 to catch over

the inner edge of said rim, and being secured by the screws 4.

When the sheet 11 is properly adjusted within the bite of the rolls, a key 17, which is adjacent to the feed-board 12, is depressed, thereby pressing down an arm 18 belonging to the same lever as the arm 8, and extending forwardly from the pivot 9. By the depression of said key, the arm 8 is lifted and stop 7 raised out of the path of the lug 6, whereupon the handle 2 may be grasped, and the stencil cylinder advanced as shown by the arrow to stencil the sheet 11; the cylinder being arrested as before upon the completion of the revolution by means of the stop 7. The downward stroke of the key may be limited by a stop 19, and the lever may be returned to normal position by a spring 20. The key 17 is of course released, as soon as the cylinder begins to turn, so as to bring the stop 7 again in the path of the lug 6.

I prefer to provide a detent 21 having an inclined face, and pressed yieldingly by a spring 22 up against an inclined bottom face 23 of the lug 6 for the purpose of holding the latter yieldingly against the stop 7, so as to prevent recoil of the cylinder when striking said stop 7. The cylinder is thus held stationary during the insertion and adjustment of the sheet 11, and it is assured that stencils will strike in the same place on all the sheets. It will be understood that during the last part of the advance rotation of the stencil cylinder, the lug 6 strikes an inclined portion 24 on said detent and forces the same down out of the way, but that the detent immediately recovers itself and holds the cylinder steady at the point where it is arrested by the stop 7.

The cylinder may be retracted or revolved backwardly independently of the stop 7, since the latter may be provided with an inclined face 25 to be engaged by an inclined face 26 formed upon the lug 6 during such backward rotation, whereby said stop 7 is lifted to permit the lug to pass thereunder; although if desired, the key 17 may be conveniently held down during successive backward rotations of the cylinder, so as to silence the stop 7, and in such case the beveled faces 25 and 26 may be dispensed with. It will also be understood that during the backward rotation of the cylinder, the lug 6 engages the inclined face 21 on the detent and forces the same down out of the way.

The pressure roll 15 is mounted by gudgeons 27 upon an open frame 28 hinged at its opposite ends at 29 upon the framework. The roll is releasably pressed up against the cylinder 1 by means of a cam 30, which is mounted upon a rock shaft 31 and engages the under side of said frame to lift it. On the end of said rock shaft is fixed an arm 32, which is turned to cause said cam to set up

the pressure roll; a latch 33 being provided to retain the arm 32 in its effective position. By releasing the latch, the arm 32 may spring or be turned up to release the roll 15 as seen at Fig. 5, the roll being shown by full lines at Fig. 1 in effective position, and by dotted lines in released position. Upon said rock shaft 31, I mount a cam 34 to engage a spur 35 formed upon the lever arm 18, so that when the roll is released, the cam 34 is turned and swings the spur 35 in a direction to lift the stop 7 to ineffective position, that is so that it will clear the lug 6, Fig. 5. Said cam has a flat side 36 against which said spur is normally pressed by the spring 20, said flat side serving therefore as a stop for the lever. Upon said rock shaft, I also mount a cam 37 to engage an arm 38 provided upon the yielding detent 21, so as to simultaneously swing said detent out of the path of the lug 6, Fig. 5. Thus when the pressure roll is released, the stop and detent are both silenced, and the stencil cylinder may be freely rotated in either direction, as is occasionally desirable, as for instance when inking the same. Upon swinging the arm 32 back to effective position, Fig. 1, the springs 20 and 22 register the stop 7 and detent 21 to active positions.

Variations may be resorted to within the scope of the invention, and portions of the improvements may be used without others, as for instance, the detent 21 may be omitted; although I prefer to use it for the reasons given, and also because when the key 17 is depressed, the detent 21 may cam the cylinder forward a little, thereby mechanically drawing the sheet 11 between the cylinder and the pressure roll, so that the position of the sheet in relation to the cylinder becomes fixed before the operator grasps the handle 2, and hence liability of accidental disarrangement of the sheet is avoided; the cam for this purpose being made of considerable length as illustrated, so as to impart a substantial movement to the cylinder.

Having thus described my invention, I claim:

1. In a stenciling machine, the combination with a rotatable stencil cylinder having a handle, of a stop for arresting the cylinder to terminate its advance rotation, a finger piece for releasing said stop, and a yielding device tending to force the cylinder against said stop.

2. In a stenciling machine, the combination with a rotatable stencil cylinder, of a stop for arresting the advance movement of the cylinder at the completion of its revolution, and a yielding pivoted arm to press said cylinder against said stop.

3. In a stenciling machine, the combination with a rotatable stencil cylinder, of a stop for arresting the advance of the cylinder at the completion of its revolution, and a

spring detent forced to yield by said cylinder just before the latter is arrested by said stop, said detent being constructed to hold the cylinder against the stop.

5. In a stenciling machine, the combination with a rotatable stencil cylinder, of a stop for arresting the advance of the cylinder at the completion of its revolution, a spring detent forced to yield by said cylinder just before the latter is arrested by said stop, said detent being constructed to hold the cylinder against the stop, and means to release the cylinder from the control of the stop.

10. In a stenciling machine, the combination with a rotatable stencil cylinder, of a stop for arresting the advance of the cylinder at the completion of its revolution, a spring detent forced to yield by said cylinder just before the latter is arrested by said stop, said detent being constructed to hold the cylinder against the stop, and means to release the cylinder from the control of the stop, both said stop and said detent being constructed to be forced aside by the cylinder during the retraction thereof.

15. In a stenciling machine, the combination with a rotatable stencil cylinder, of an arm adjustably mounted thereon and having a lug, a pivoted arm on the framework having a stop to be engaged by said lug to arrest the advance of the cylinder at the completion of its revolution, and a spring and stop for said pivoted stop arm.

20. In a stenciling machine, the combination with a rotatable stencil cylinder, of a device for arresting the advance of the cylinder at the completion of its revolution, and yielding means for preventing recoil of the cylinder from said arresting device, and means for releasing the cylinder.

25. In a stenciling machine having a feed-board, the combination with a rotatable stencil cylinder, and a pressure roll constructed to co-operate to gage the leading edges of the paper sheets, a lever pivoted upon the framework, and having a depressible arm extending to the feed-board, a stop provided upon the end of said lever, an arm provided upon the stencil cylinder and having a lug or part to engage said stop to arrest the advance of the cylinder at the completion of its revolution, said stop and lug being beveled to enable the lug to force the stop aside during the retraction of the cylinder, and a spring for said stop.

30. In a stenciling machine, the combination with a rotatable stencil cylinder, of a stop for arresting the advance of the cylinder at the completion of its revolution, a yielding detent for holding said cylinder against said stop, and means for silencing both said stop and said detent.

35. In a stenciling machine, the combination with a rotatable stencil cylinder and a pressure roll, of a device for arresting the ad-

vance of the cylinder at the completion of its revolution, means for releasing said pressure roll, and means controlled by said roll-releasing means, for silencing said cylinder arresting device.

40. In a stenciling machine, the combination with a rotatable stencil cylinder, of a device for arresting the advance of the cylinder at the completion of its revolution, a manually operable device for releasing said cylinder from said arresting device to permit the cylinder to make another revolution, and to be again arrested at the completion thereof, and independently operable means for silencing said arresting device.

45. In a stenciling machine, the combination with a rotatable stencil cylinder, of a device for arresting the advance of the cylinder at the completion of its revolution, a manually operable device for releasing said cylinder from said arresting device to permit the cylinder to make another revolution, and to be again arrested at the completion thereof, independently operable means for silencing said arresting device, a pressure roll for said cylinder, and means connected with said silencing means for releasing said pressure roll.

50. In a stenciling machine, the combination with a rotatable stencil cylinder, of a device for arresting the advance of the cylinder at the completion of its revolution, a manually operable device for releasing said cylinder from said arresting device to permit the cylinder to make another revolution, and to be again arrested at the completion thereof, independently operable means for silencing said arresting device, a pressure roll for said cylinder, means connected with said silencing means for releasing said pressure roll, a yielding detent for holding said cylinder against said arresting device, and means connected with said silencing means for simultaneously silencing said detent.

55. In a stenciling machine, the combination with a stencil cylinder and a pressure roll, of a rock shaft having means for pressing said roll against the cylinder, a latch for holding said rock shaft in effective position, a lever having a stop for arresting the cylinder, and also having an arm extending to said rock shaft, and a cam upon the rock shaft to throw said stop out of effective position when said rock shaft is released from said latch, to permit the cylinder to be rotated independently of said stop.

60. In a stenciling machine, the combination with a stencil cylinder and a pressure roll, of a rock shaft having means for pressing said roll against the cylinder, a latch for holding said rock shaft in effective position, a lever having a stop for arresting the cylinder, and also having an arm extending to said rock shaft, a cam upon the rock shaft to throw said stop out of effective position when said

rock shaft is released from said latch, to permit the cylinder to be rotated independently of said stop, a pivoted lever having a spring and caused by said spring to hold the cylinder 5 yieldingly against said stop, and also having an arm extending to said rock shaft, and a cam upon the rock shaft to engage said arm and swing it to ineffective position when the pressure roll is released.

16. In a stenciling machine, the combination of a stencil cylinder, a stop therefor, a yielding detent, and means for simultaneously silencing said stop and detent.

BURNHAM C. STICKNEY.
